UNITED STATES PATENT OFFICE.

BENJAMIN F. SLENKER, OF PANOLA, ILLINOIS.

GRAIN-LOADER.

SPECIFICATION forming part of Letters Patent No. 700,097, dated May 13, 1902.

Application filed May 24, 1900. Serial No. 17,873. (No model.)

To all whom it may concern:

Be it known that I, BENJAMIN F. SLENKER, a citizen of the United States, residing at Panola, in the county of Woodford and State of Illinois, have invented certain new and useful Improvements in Grain-Loaders, of which the following is a specification.

This invention relates to novel means for loading grain from a grain-storage house into railway-cars, and has for its object to accomplish such a result in an expeditious, economical, and convenient manner and in which the grain can be loaded into the car in a satisfactory manner at a minimum of time, labor, and expense.

To these ends my invention consists in the features and in the construction, combination, and arrangement of parts hereinafter described, and fully pointed out in the claims following the description, reference being had to the accompanying drawings, forming a part of this specification, wherein—

Figure 1 is a view in side elevation of my improved apparatus. Fig. 2 is a detail view, in front elevation, of the portable grain-discharging device. Fig. 3 is a top plan view of the driving-gearing. Fig. 4 is an end elevation of the fan, and Fig. 5 is a detail view of a part of the same.

Referring to the drawings, the numeral 1 indicates the side wall of a part of a building in which the grain is supposed to be stored, and 2 a bracket fixed to said wall and provided with a bearing 3, in which is journaled 35 a shaft 4, that may be driven from any suitable source of power, preferably located inside the building. On the shaft 4 is fixed a beveled gear-wheel 5, and loosely journaled or sleeved on said shaft is a frame 6, in which 40 is journaled one end of a shaft 7, on which is fixed a beveled pinion 8, that gears with the beveled wheel 5. To the end of the shaft 7 is connected, by means of a universal coupling 9 of ordinary and well-known construction, a shaft 10, the other end of which shaft is coupled in like manner by means of a coupling 11 to the fan-shaft 12.

The numeral 13 indicates a closed casing, preferably formed of sheet-iron and provided 50 centrally on its opposite sides with bearings 14, in which the fan-shaft 12 is journaled. The bearings 14 are attached to the upper

ends of legs or supports 15, between which the casing may be tilted. On the opposite sides of the casing are formed angularly-disposed laterally-extending flanges 15, separated to an extent somewhat greater than the distance between the opposite sides of the legs and forming fixed limits of movement for the tilting adjustment of the casing. The 60 casing carries a rod 14', extending out through a slot 16' in each of the angular connecting-plates for the legs, said rod having a threaded end for the reception of a set-screw 16, as most clearly shown in Fig. 2 of the drawings. 65 On the fan-shaft within the casing is fixed a fan comprising a hub 17, provided with a plurality of radial arms 18, to the opposite sides of the outer ends of which are clamped fan-blades 19, the purpose of the double arrangement of fan-blades on each arm being to make both sides of the fan alike, whereby the operation will be the same irrespective of the direction in which the fan is run. The bottom of the casing is curved, as shown, and in 70 the lower side of each end thereof is formed a discharge-opening 20, adapted to be closed by a sliding cover 21. In one side of the casing, near its opposite ends and upper edge, are formed two feed-openings 22 and 23, and 75 between and common to both is a swinging cover 24, the arrangement being such that the cover may be turned to close either of the feed-openings and open the other.

The operation of my improved device is as 80 follows: The car to be loaded is run up alongside the building and the casing and its supports are arranged in the car. The grain-spout (shown in Fig. 1 by dotted lines) is inserted in one of the feed-openings and the other is closed by the cover 24. Let it be assumed that the spout is inserted in the opening 22 and that the opening 23 is closed. The discharge-opening 20 on the left or adjacent to the opening 22 will be opened, and the corresponding feed-opening at the opposite end of the casing will be closed. The driving mechanism will then be put into operation to rotate the fan in the direction of the hands of a clock, and the grain will be rapidly and forcibly discharged to the left of the machine and to the end of the car. By placing the spout in the opening 23 and closing the opening 22, closing the discharge-opening on the

left and opening that on the right, and reversing the direction of rotation of the fan the grain will in like manner be discharged to the right or to the other end of the car. By 5 tilting the casing, as shown, the vertical height of discharge of the grain may be altered or adjusted to gradually throw the grain higher as the car fills up, the casing being tilted to any desired angle and locked in its 10 adjusted position by the thumb-screw 16. By means of providing the shaft 10 with universal couplings, as shown, the casing may be freely moved about, as desired, without disturbing the driving mechanism.

15 As shown, the bracket 6 may be freely rotated or swung about the shaft 4, and to the side of the building is connected one end of a rod 25, the other end of which is provided with a hook which may be hooked into a lug 20 26 on the bracket-arm, and thus hold the latter horizontal in operative position. By unhooking the rod the gearing may be permitted to drop down alongside of the building when the device is not in use, whereby it 25 will be out of the way of the cars.

Having described my invention, what I claim is—

1. The combination in a grain-loader, of a portable support, a casing arranged thereon 30 and adapted for tilting adjustment to vary the height of its discharge, said casing being provided with a curved or concaved bottom and having discharge-openings at its opposite ends, means for independently closing said 35 openings, the side of the casing being pro-

vided with two grain-inlet openings, a pivoted cover for closing either of said openings, and a reversible rotary fan mounted in said casing.

2. The combination in a grain-loader, of a portable support, a shaft mounted in bearings 40 thereon, a casing carried by the shaft and adapted for tilting adjustment, a locking-rod carried by the casing and adapted to slots in the support said casing having discharge-openings at each end, means for independently closing said openings, the side of the casing being provided with two grain-inlet openings, means for closing said openings, and a reversible rotary fan in said casing, substantially as specified. 45

3. The combination in a grain-loader, of a portable casing provided with a discharge-opening, a fan therein, a bracket hinged to a fixed support, a rod detachably connected to the bracket and adapted to support the 50 same in position, driving-gearing in part supported by the bracket, a power-transmitting shaft connected by universal couplings to the driving-gearing and to the fan-shaft, the arrangement being such that when the bracket 55 is released the driving mechanism will fall by gravity vertically alongside the fixed support.

In testimony whereof I affix my signature in presence of two witnesses.

BENJAMIN F. SLENKER.
